GEORGE D. HADLEY, OF CINCINNATI, OHIO.

Letters Patent No. 66,326, dated July 2, 1867.

IMPROVEMENT IN STOP-COCKS.

The Schedule referred to in these Letters Patent and making part of the same.

TO ALL WHOM IT MAY CONCERN:

Be it known that I, GEORGE D. HADLEY, of Cincinnati, in the county of Hamilton, and State of Ohio, have invented a new and useful improvement in Water-Cocks; and I do hereby declare that the following is a full, clear, and exact description thereof, which will enable others skilled in the art to make and use the same, reference being had to the accompanying drawing forming part of this specification.

This improvement relates to a new and improved method of constructing water-cocks to be used for hydrants and in similar situations; and the invention consists in forming the seat of the valve in a globe shell, and in the peculiar formation of the valve, and also in the manner in which it is operated, as I will proceed to describe.

The drawing represents a vertical central section of the cock, showing plainly the parts of which it is composed, and the manner of their arrangement.

A represents the shell of the cock, the inner chamber of which is a globular cavity, in which the valve works. B is the valve; C is the valve-stem; D is the cap; D' is an elastic disk; E is an eccentric lever by which the valve is operated. The cap D screws down on to the shell with an elastic disk, composed of rubber, or some equivalent substance, between it and the shell, as seen in the drawing. This elastic disk or valve is slipped over the spindle or valve-stem, and springs into a groove which is turned for it in the stem. This keeps and insures a tight joint, and at the same time it acts as a cushion to prevent the too sudden closing of the valve under the pressure of the water. The lower side of the valve has guides attached to it, which are indicated by α . The valve is operated by a lever, whose lower end is so attached to the valve-stem that it raises the valve by a gradual motion as the lever is lowered; the lower end of the lever being attached to the stem eccentrically, and with the eccentric bearing on the top of the cap D. This movement, in combination with the elastic disk, prevents injury to the valve by any sudden jerking or rapid movement.

What I claim as new, and desire to secure by Letters Patent, is—

The eccentric lever, by which the valve is operated, the elastic disk D'; the cap D confining the disk D' and the valve B with its guides α , in combination with the shell of a water-cock, the whole constructed and arranged substantially as herein shown and described for the purposes set forth.

GEO. D. HADLEY.
